UNITED STATES PATENT OFFICE.

JOHN VANDEVER WELLS, OF NEW YORK, N. Y., ASSIGNOR OF ONE-FOURTH TO JOHN YUENGLING, OF MORRISTOWN, NEW JERSEY.

PUZZLE.

1,377,039.

Specification of Letters Patent.

Patented May 3, 1921.

Application filed April 17, 1920. Serial No. 374,620.

To all whom it may concern:

Be it known that I, JOHN VANDEVER WELLS, a resident of the city of New York, borough of Manhattan, county and State of New York, have invented a new and Improved Puzzle, of which the following is a full, clear, and exact description.

This invention relates to puzzles, and has reference more particularly to railroad puzzles and the construction of same.

An object of this invention is to provide a puzzle which will be instructive and highly amusing to both old and young.

Another object of this invention is to provide a simple construction for the puzzle which may be easily and cheaply made.

Reference is to be had to the accompanying drawing forming a part of this specification, in which it is understood that the drawing illustrates only one form of the invention, and in which—

Figure 1 is a plan view of one-half of the box which contains one of my improved railroad puzzles.

Fig. 2 is a plan view of the other half of the box showing another of my railroad puzzles.

Fig. 3 is a section through the box and the puzzles on the line 3—3 of Fig. 2.

Fig. 4 is a sectional view on a large scale through the puzzle on the line 4—4 of Fig. 2.

Fig. 5 is a sectional view on a large scale through the puzzle on the line 5—5 of Fig. 2.

Fig. 6 is a central sectional view on a large scale through one of the cars used in my puzzles.

Fig. 7 is a longitudinal sectional view through the car shown in Fig. 6.

Referring to the accompanying drawing by numerals, 10 indicates a rectangular box having a bottom 11, said box telescoping into a similar rectangular box 12 having a bottom 13. The two boxes 10 and 12 are spaced apart by means of a rib 14 formed in the box 10. While I have illustrated a railroad puzzle in each of the boxes 10 and 12, I wish most particularly to protect my improved construction for making the puzzles and do not wish to limit myself to either of the railroad problems shown, since manifestly a great variety of railroad puzzles can be made with my improved construction with slight modifications of same.

I will now describe the puzzle shown in

the box 12 which consists of a main line track 15 into which leads the branches 16 and 17 of a Y side track. A double sliding switch 18 is provided at the junction of each branch 16 and 17 with the main line 15, and a single switch 19 is provided at the junction of the two branches 16 and 17. The inside of the branches 16 and 17 and the inside of the main line 15 adjacent said branches are provided with fingers 15_a which extend through perforations in the bottom 13 so as to hold said branches and main line in place. My puzzles are preferably made of stamped metal and consist of the bottom 13 from which upwardly extending oblique flanges 21 are formed which comprise the railroad tracks, and these oblique flanges engage oblique flanges 22 formed in a bottom 23 of railroad cars having sides 24. The sides 24 are provided on 70 their top edges with outstanding flanges 25 which are engaged by an offset flange 26 of a top 27 which may be arcuate in cross section. It is desired to make the entire 75 puzzle construction, including the cars, of 80 stamped metal so that it can be cheaply cut and pressed into shape by the use of dies. Oblique upstanding flanges 28 are formed in the bottom 13 which engage oblique 85 downwardly extending flanges 29 formed on each side of the switches 18 and 19 so as to guide the switches as they are reciprocated on the bottom 13. Each of the switches 18 and 19 is provided with a recess 30 which may be engaged by the finger 90 in sliding the switches back and forth under the flanges 28. The track in the switches 18 is formed by oblique upstanding outside flanges 31 between which is secured a center piece 31_a having offset flanges 31_b clenched 95 under said switch, and the flanges 29 of each switch are made to pass the rails 15 by undercutting said rails at an oblique angle 32, so that said rails also serve as 100 guides for said switches. The movement of the switches 18 is limited on one end by a side of the box 12, and is limited on the other end by an upstanding flange 33 formed from the bottom 13. A pair of upstanding flanges 34 are formed from the bottom 13 105 and limit the movement of the switch 19 so that in each extreme position, its car track will register with one of the branches 16 or 17. In the puzzle shown in Fig. 1, preferably two cars designated by the nu- 110

meral 35 are provided, and one locomotive 36, on which an arrow 37 is inscribed, while numerals 38 are inscribed on the cars 35. The object of the puzzle is to so move the cars 35, the locomotive 36, and manipulate the switches 18 and 19 that the position of the two cars 35 will be reversed without reversing the direction of the locomotive 36. Furthermore, neither of the cars 35 can be moved independently without being attached to the locomotive 36, and all the switches have a capacity for only one car or locomotive at a time.

In the puzzle shown in Fig. 2, two locomotives 36 are provided with a number of cars 35 forming two trains. A stationary side track 39 having capacity for holding one car or locomotive, is secured to the bottom 11 of the box by means of fingers 40 extending through perforations in said bottom and clenched on the underside thereof. The main line 15, is provided with one switch 41 constructed similar to the switches 18 of Fig. 1, so that cars may be transferred from the main track to the side track 39. The object of the puzzle shown in Fig. 2 is to reverse the position of the two trains by manipulating the switch 41, always moving a car with a locomotive. Each of the bottoms 11 and 13 may be offset and labels 42 may be pasted thereto which will serve to cover up the holes formed by the upturned flanges, and will also carry directions for the operation of the puzzles.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim as new and desire to secure by Letters Patent:

1. In a railroad puzzle, a metal box provided with a bottom, a plurality of upstanding oblique flanges formed in said bottom positioned in pairs and adapted to form railroad tracks, a plurality of metal cars, a plurality of downwardly extending oblique flanges formed on the bottom of each car adapted to be slidably received by the track

flanges, and a plurality of switches associated with said tracks. 55

2. A device as described in claim 1, characterized by a downwardly extending oblique flange formed on each side of said switches adapted to be slidably received by said guide flanges, a track formed in each switch adapted to register with one track when said switch is moved to one extreme position and to register with another track when said switch is moved to a second extreme position, and means for moving said switch. 60

3. In a railroad puzzle, a metal box provided with a bottom, a plurality of track flanges formed in said bottom, a plurality of guide flanges formed in said bottom, a plurality of switches slidably received by said guide flanges, said track flanges being also adapted to slidably receive said switches, and a plurality of cars slidably connected with said track flanges. 70

4. In a puzzle, a metal box, a plurality of oblique track flanges formed in said box, a plurality of switches slidably associated with said track flanges, a plurality of branch tracks associated with said box, and a plurality of fingers associated with said branch tracks adapted to extend through perforations in said box so as to secure said branch tracks to said box. 75

5. In a puzzle, a metal box, a cover therefor, a plurality of oblique track flanges formed in said box, a plurality of switches slidably associated with said tracks, a plurality of cars having bottoms and sides, a plurality of outstanding flanges formed on said sides, a plurality of offset flanges formed on said cover adapted to engage said outstanding flanges so as to secure said cover to said sides, and a plurality of downwardly extending oblique flanges formed on the bottom of each car adapted to be slidably received by said track flanges. 90

6. In a railroad puzzle, a metal box, a plurality of oblique track flanges formed in said box, a plurality of switches slidably associated with said tracks, a plurality of upstanding flanges formed in said box adapted to limit the movement of said switches, and a plurality of cars slidably connected to said tracks. 95

JOHN VANDEVER WELLS.
